UNITED STATES PATENT OFFICE.

DAVID T. MAY, OF NEW YORK, N. Y., ASSIGNOR TO WESTERN ELECTRIC COMPANY,
INCORPORATED, OF NEW YORK, N. Y., A CORPORATION OF NEW YORK.

PROTECTIVE DEVICE.

1,319,720.

Specification of Letters Patent. Patented Oct. 28, 1919.

Application filed January 18, 1918. Serial No. 212,472.

To all whom it may concern:

Be it known that I, DAVID T. MAY, a citizen of the United States, residing at New York, in the county of New York, State of New York, have invented certain new and useful Improvements in Protective Devices, of which the following is a full, clear, concise, and exact description.

This invention relates to protective devices for use in electric circuits exposed to lightning or like hazards, and is of the type which comprises a spark gap inclosed in a container from which practically all the gas has been exhausted.

As is well known, there is for each length of spark gap a critical gas pressure at which the breakdown voltage, *i. e.*, the voltage that will force a discharge across the gap rather than through the portion of the line protected thereby, is a minimum, and in practice the container is exhausted to about this pressure. If, through the cracking of the walls of the container or from other causes, the pressure in the container increases beyond a certain point, the breakdown voltage is so much increased that the gap no longer affords a path of discharge for all voltages that would be injurious to the apparatus to be protected. It has been proposed to provide protection devices of this type with automatic means for conductively bridging the spark gap when the pressure rises beyond the limit of safety, but although this maintains the protective function of the device it results in grounding the line until the defective arrester is replaced by one whose spark gap is unbridged.

The device of this invention includes two alternative spark gaps of different lengths and therefore having different critical pressures, in consequence of which one gap provides protection at the normal pressure in the container, and the other gap provides protection when the pressure unduly increases beyond that for which the first gap is designed. A similar arrangement is covered by the application filed by George H. Stevenson, Serial No. 132,446, filed November 20, 1916, for protective devices, assigned to the same assignee as the present application. This invention is an improvement thereon in that selective means are provided for interposing one or the other of said gaps in the path, which must be followed by a discharge through said device, the other

gap being at the same time removed from the discharge path.

In the accompanying drawing, Figure 1 is a cross-sectional view of one embodiment of my invention; Fig. 2 is a similar view of a modified form; and Figs. 3 and 4 are diagrams of the circuit arrangements of the devices shown in Figs. 1 and 2 respectively.

In a container 1 are arranged electrodes 2, 4 and 6 of any suitable material. Between electrodes 2 and 4 is placed an insulating separator 10 and between electrodes 4 and 6 is placed a second insulating separator 12 of greater thickness than the separator 10. There are thus formed two spark gaps of different lengths, the longer spark gap—between the electrodes 4 and 6—being usually of the length best suited to the conditions under which the device is to be used.

In manufacturing the arrester, the container 1 is exhausted to the degree of vacuum that will give the most efficient operation of the longer spark gap, and while the degree of vacuum exists the discharge path includes this longer spark gap. But if, on account of leakage or ionization of the metal of the electrodes or from other causes, the gas pressure in the container rises beyond that at which the longer spark gap functions properly, this gap is removed from the discharge path and replaced by the shorter gap between the electrodes 2 and 4.

To effect the substitution in the discharge path of one spark gap for the other, there is provided a manometric valve or switch, 90 which in form shown by Fig. 1, is constructed and operated as follows: A U-shaped tube 14 is supported in the container on the stem 15. One end 16 of the tube is closed and the other end 18 is open and covered by a porous cap 20 which permits passage of air or other gas into and out of the tube. Within the tube is the mercury column 22.

Brackets 24 and 26, of suitable conductive material, support the electrodes and are conductively connected to electrodes 2 and 6 respectively; each bracket is secured to one of the legs of the U tube by a band 28 or the like. Each of the leading-in conductors 30 and 32 forming the terminals 105 of the arrester and hermetically sealed into the stem 15 is connected to one end of one of the conducting brackets 24 and 26. To the other end of the bracket 24 is connected the conductor 34 which passes through the

porous cap 20 and extends into the interior of the manometer tube 14. To the other end of bracket 26 is connected the conductor 36, which extends into the interior of the manometer tube through its closed end 16. From the electrode 4 leads conductor 38 which is hermetically sealed into the wall of the base of the manometer tube with its end extending into the mercury column 22.

The parts are so proportioned and arranged that, with the pressure in the container that at which the longer spark gap between the electrodes 4 and 6 is adapted to function satisfactorily, the mercury column 22 rests in the position shown in Fig. 1, that is, with the mercury enveloping the end of the conductor 34. The path of discharge then includes leading-in conductor 30, conductor bracket 24, conductor 34, mercury column 22, conductor 38, electrode 4, the longer spark gap, electrode 6, conducting bracket 26 and the leading-in conductor 32. This condition is diagrammatically shown in Fig. 3 in which the conventional symbols denoting the various parts of the circuit are indicated by the same reference characters as are used in Fig. 1.

If the pressure in the container rises, the mercury column 22 is forced toward the closed end 16 of the tube until, when a certain pressure is reached, the contact between the end of the mercury column and the conductor 34 is broken, and the opposite end of the mercury column surrounds and makes contact with the end of the conductor 36. The path of discharge then includes conductor 30, conducting bracket 24, electrode 2, shorter spark gap, electrode 4, conductor 38, mercury column 22, conductor 36, conducting bracket 26 and leading-in conductor 32.

The position of the ends of the conductors 34 and 36 and the length of the mercury column 22 is such that the contact between the conductor 34 and the mercury column is broken, and contact between conductor 36 and the mercury column is made whenever the pressure in the container becomes high enough to prevent the reliable functioning of the longer spark gap. When the pressure is again reduced by reëxhausting the container, or otherwise, the mercury column returns to the position shown in Fig. 1 and the longer spark gap is restored to the discharge path. Thus there results an automatic selective inclusion in the arrester discharge path of the spark gap functioning most satisfactorily at the gas pressure existing in the container.

In the arrangement shown in Figs. 1 and 3, the removing of each spark gap from the discharge path is secured by short-circuiting the gap. In the modified arrangement shown in Figs. 2 and 4, the remov-

ing of the spark gap is secured by cutting it entirely out of the circuit. In the modified arrangement, the leading-in conductor 40 is sealed into the wall of the base of manometer tube 14 with its end extending into the mercury column 22, and the leading-in conductor 42 is connected to the middle electrode 4. The electrodes 2 and 6 are connected through the conductive brackets 24 and 26 respectively to the conductors 44 and 46. Conductor 44 passes through the closed end 16 of the manometer tube 14 and the conductor 46 is led through the porous cap 20 into the open end 18 of the manometer tube.

With the pressure in the container 1 that at which the longer gap functions satisfactorily, the mercury column is in the position shown in Fig. 2 and the discharge path includes leading-in conductor 40, mercury column 22, conductor 46, conductor brackets 26, electrode 6, the longer spark gap, electrode 4 and leading-in conductor 42. When the pressure exceeds that at which the longer gap can be relied upon, the mercury column is moved toward the closed end 16 of the tube, breaking contact with conductor 46 and making contact with the conductor 44. The discharge path is then through leading-in conductor 40, mercury column 22, conductor 44, conductor bracket 24, electrode 2, shorter spark gap, electrode 4 and leading-in conductor 42.

It is apparent that if the conditions of an installation should make such a course desirable, either of the above forms of my invention could be arranged with the shorter spark gap normally in the discharge path, a change in pressure resulting in the substitution of the longer gap therefor.

What is claimed is:

1. In a protective device arranged to afford a discharge path for electrical charges and comprising two spark gaps, selective switching means for including one or the other of said spark gaps in said discharge path.

2. In a protective device arranged to afford a discharge path for electrical charges and comprising two spark gaps of different lengths, selective switching means for including one or the other of said spark gaps in said discharge path.

3. In a protective device, a pair of conductors forming the terminals of said device, electrodes providing spark gaps of different lengths, and switching means for selectively connecting said conductors to the electrodes at the opposite ends of one or the other of said spark gaps.

4. In a protective device, a pair of conductors forming the terminals of said device, electrodes providing spark gaps of different lengths, and automatic switching means for selectively connecting said con-

- ductors to the electrodes at the opposite ends of one or the other of said spark gaps.
5. In a protective device, a container, a pair of conductors entering said container and forming the terminals of said device, electrodes in said container providing spark gaps of different lengths, and means controlled by the gas pressure in the container for selectively connecting said conductors to the electrodes at the opposite ends of one or the other of said spark gaps.
6. In a protective device, a container, a pair of conductors entering said container and forming the terminals of said device, electrodes in said container providing spark gaps of different lengths, and a manometric switch in said container for connecting said conductors to the opposite ends of one or the other of said spark gaps.
- 20 7. In a protective device, a container, a pair of conductors entering said container and forming the terminals of said device, electrodes in said container providing spark gaps of different lengths, and means for selectively connecting said conductors to opposite ends respectively of one or the other of said spark gaps, said means comprising a U-shaped tube communicating at one end with the interior of said container and closed thereto at the other end, a column of mercury in said tube, and contacts spaced along

the interior of said tube and connected to the respective electrodes and conductors.

8. In a protective device, a partially evacuated container, electrodes therein providing discharge gaps of different lengths, said electrodes being surrounded by gas at substantially the critical pressure of the longer gap, a pair of conductors forming the terminals of said device, the longer of said gaps being interposed between said conductors, and means operating in response to an increase of gas pressure in said container to substitute the shorter gap for the longer gap.

9. In a protective device, a partially evacuated container, a pair of conductors entering said container and forming the terminals of said device, electrodes in said container providing a plurality of spark gaps adapted to different degrees of vacuum, said conductors being connected to electrodes at opposite ends of one of said spark gaps, and switching means responsive to a change of gas pressure in the container for connecting said conductors to electrodes at the opposite ends of a different spark gap.

In witness whereof, I hereunto subscribe my name this 12th day of January, A. D., 1918.

DAVID T. MAY.
